UNITED STATES PATENT OFFICE.

FRED MACCARONE AND FRANK T. GENTILE, OF BROOKLYN, NEW YORK, ASSIGNEES,
BY DIRECT AND MESNE ASSIGNMENTS, TO MACCARONE CO., INC., A CORPORATION
OF NEW YORK.

REMOVABLE TOP LIFT FOR SHOE HEELS.

Application filed June 16, 1928. Serial No. 285,826.

This invention relates to removable top lifts for shoe heels.

One of the objects of our invention is to provide a detachable lift for a shoe heel which may be quickly positioned on a leather 5 or wooden heel without special tools or instruments.

Another object of our invention is to provide a detachable and replaceable heel lift for either men, women or children's shoes in 10 which the body of the heel is constructed to receive a sleeve for interlocking connection with a second sleeve permanently attached to the heel lift.

To enable others skilled in the art to more 15 fully comprehend the underlying features of our invention and its general application to shoe heels, reference is had to the accompanying drawing showing a preferred embodiment wherein

20 Fig. 1 is a view showing the heel of a shoe in section and to which our invention is applied.

Fig. 2 is a top plan showing the sleeve and 25 top lift.

Fig. 3 is a side view showing the sleeve and top lift before their assembly.

Fig. 4 is a section showing the heel sleeve.

Fig. 5 is a transverse sectional view through the heel sleeve.

30 Fig. 6 is an enlarged sectional view of the interlocking sleeve and top lift, in position.

Referring now to the drawings, 5 designates the shoe upper of a conventional type or style of shoe having a wood, leather or other composition of shoe heel 6 to which our invention is applicable. Within the body of the heel proper there is provided a triangular, vertical opening or recess of considerable depth in which is permanently fixed a triangular, metallic sleeve 7. The opening or recess and the sleeve is preferably positioned in the center of the heel body proper. Each wall of the sleeve 7 is provided with a depression 8 near the bottom thereof.

45 Constructed and arranged for detachable interlocking connection with the sleeve 7 is an interior top lift sleeve 9 also triangular in cross section and formed of the same material as the first mentioned sleeve. The sleeve 9 is slightly shorter than the sleeve 7 so that it may telescope and be frictionally locked therewith. The sleeve 9 therefore is also

provided with depressions 10 on each wall which are adapted to lock in the depressions 8 of the first mentioned sleeve, due to the resiliency of the metal. The bottom of each wall of the interior sleeve is formed with laterally bent prongs 11 which are adapted to be clinched to the body of the lift 12 to be permanently attached therewith. By forcing 60 or driving the inner sleeve within the heel sleeve, the top lift may be seated on the bottom of the heel without resorting to the aid of screws, nails or other fastening devices.

65 From the above construction, it will be seen that the top lift and the attached sleeve constitutes an article of manufacture that may be sold with the shoes or with the heels to the shoe manufacturer and that the top lift may be replaced from time to time when it begins to wear. In removing the top lift and the attached sleeve, the same may be discarded and a new one replaced, or the right and left top lifts may be interchanged if it 70 is found that the lift has begun to wear. In any event, it is to be understood that the complete article of manufacture resides in the 75 triangular sleeve and top lift which cannot rotate relative to the heel sleeve when the 80 said sleeves are thus interlocked. While we have shown the sleeve 9 attached to the top lift by prongs, it will be understood that other attaching or locking means may be resorted to in uniting said sleeve and top lift. In 85 the same manner the inner and outer triangular sleeves may be detachably interlocked in various mechanical means for the obvious purpose.

90 While we have shown and described our invention with some degree of particularity, it will be realized that other modifications and changes may be resorted to under special conditions. We therefore do not wish to be limited and restricted to the exact details 95 shown and described but reserve the right to make such changes and modifications as may fairly fall within the scope of the subject matter now being claimed.

Having shown and described our invention, what we claim as new and desire to secure by Letters Patent is:—

100 In combination, a shoe heel having a small contracted lower end relative to its upper end and of substantially greater length than 105

width, and having an axial opening extending nearly to its upper end and of irregular cross section, a stiff metallic sleeve of greater length than width and corresponding in cross section to said axial opening and extending to the upper end thereof and having a depression therein; a resilient metal interior top lift sleeve extending substantially the length of said axial opening and having a de-

pression adapted to interlock with the said 10 depression formed in the first mentioned sleeve in removable relation thereto, and having prongs formed integral therewith, and a lift carried by said prongs.

In testimony whereof we affix our signatures.

FRANK T. GENTILE.
FRED MACCARONE.
